COMBINATION HAIR DRIER AND LIQUID SPRAYER

Lawrence M. Collins, Galax, Va.

Application July 21, 1934, Serial No. 736,424

3 Claims. (Cl. 299—89)

The invention relates to a combination hair drier and liquid sprayer.

The primary object of the invention is the provision of a device of this character, wherein liquid for the treatment of the hair of persons can be conveniently sprayed from a receptacle and the spraying being had through air under pressure, there being a control for the motive power and for the air under pressure and this control being conveniently arranged so that it can be manually operated.

Another object of the invention is the provision of a device of this character, wherein the construction thereof is novel to permit the said device to be utilized as a hair drier or a liquid sprayer for the spraying of liquids as commonly used for the treatment of the scalp and hair of a person.

A further object of the invention is the provision of a device of this character which is simple in construction, thoroughly reliable and efficient in its operation, conveniently handled, readily convertible for use as a sprayer or a drier, easy of operation, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:

Figure 1 is a fragmentary vertical longitudinal sectional view through the device constructed in accordance with the invention and showing diagrammatically the electrical hook-up for the same.

Figure 2 is a side elevation partly in section of a nozzle used when the device is employed as a hair drier.

Figure 3 is a side elevation partly in section of the motor and fan employed with the device.

Figure 4 is a vertical transverse sectional view through the fan.

Similar reference characters indicate corresponding parts throughout the several views in the drawing.

Referring to the drawing in detail, in the illustration given, the device comprises an electric motor 10, a fan casing 11, which is attached to one end of the motor casing, and the rotary fan wheel 12 arranged within the casing 11 and driven directly from the power shaft of said motor

10. This casing 11 for the fan wheel has the air intake ports 13, and through the medium of a union 14 has connection with a hose 15 for coupling with an air and spray gun.

The gun comprises a barrel 16 having a handle 17, the latter being in the form of a pistol grip handle. The handle 17 has formed therein in a passage 18 for communication with the bore of the barrel 16 and within this passage is a tubular electric heating unit 19, it being arranged in an electric circuit 20 having the motor 10 therein. The wires of the circuit 20 are trained through the handle 17 and such circuit is opened and closed by a hand operable switch 21 fitted within the handle 17 and having a trigger 22, 5 manually operated. The switch 21 is normally held in open position by an expansion spring 23 as mounted within the handle 17. The switch 21 has combined therewith a cut-off valve 24 which opens and closes the communication between the passage 18 and the barrel 16, the valve 24 being normally in closing position when the switch 21 has opened the circuit 20. The passage 18, at the free end of the handle 17, has fitted therewith a nipple 25 to which is connected 10 the hose 15.

Detachable from the barrel 16 is a nozzle 26 formed with a head 27 with which is detachably engaged a receptacle or bottle 28 for containing the liquid to be sprayed through the nozzle 26, the liquid in the receptacle or bottle 28 being lifted through the tube 29 into the nozzle 26 under air pressure admitted through a port 30 formed in the head 27 and leading into the said receptacle or bottle 28. This port is regulated by a screw 35 valve 31, the barrel 16 and the nozzle 26 being communicative with each other. The nozzle 26 is detachably coupled, at 32, to the barrel 16, and in lieu of the nozzle 26 there can be attached the blower nozzle 33, it being detachably engageable, at 32, with the barrel 16.

In the operation of the device, when the nozzle 26 is attached, on depressing the trigger 22 the switch 21 will close the circuit 20 and the valve 24 will open communication between the passage 18 and the barrel 16. Upon closing of the circuit, the motor 10 will drive the fan 12 and thus forcing air through the hose 15, passage 18 and barrel 16 into the nozzle 26, a portion of said air 40 under pressure being admitted to the receptacle or bottle 28 for the lifting of the liquid therein and the discharge of said liquid under pressure from the nozzle 26.

If it is desired to use the device as a hair drier 55

the nozzle 26 is detached and in lieu thereof is substituted the nozzle 33.

It will be apparent that the air under pressure passing through the passage 18 in the handle 17 5 will become heated by the heating element 19 which is active on the closing of the circuit 20.

When pressure has been relieved from the trigger 22, the valve 24 shuts off communication between the barrel 16 and passage 18 in the handle 17 and simultaneously the switch 21 opens 10 the circuit 20, so that the motor becomes passive.

What is claimed is:

1. A device of the character described comprising a gun having a barrel and handle, the latter being of a pistol grip form and provided with a 15 passage communicating with the barrel, a discharge nozzle removably fitted with said barrel, an electric circuit including a motor, a trigger switch fitted in said handle and included in said 20 circuit for the opening and closing thereof, a fan operated by the motor and having communication with the passage in the handle for supplying air under pressure thereto, a liquid container connected with the barrel and in communication therewith, a valve in the handle for opening and closing communication between the passage in the handle and said barrel and carrying the switch, and an electric heating unit within 25 the passage in the handle and included in said 30 circuit.

2. A device of the character described comprising a gun having a barrel and handle, the latter being of a pistol grip form and provided with a passage communicating with the barrel, a discharge nozzle removably fitted with said 35 barrel, an electric circuit including a motor, a

trigger switch fitted in said handle and included in said circuit for the opening and closing thereof, a fan operated by the motor and having communication with the passage in the handle for supplying air under pressure thereto, a liquid container connected with the barrel and in communication therewith, a valve in the handle for opening and closing communication between the passage in the handle and said barrel and carrying the switch, an electric heating unit within 10 the passage in the handle and included in said circuit, and a finger engaging piece on the valve and arranged forwardly of the handle. 5

3. A device of the character described comprising a gun having a barrel and handle, the latter being of a pistol grip form and provided with a passage communicating with the barrel, a discharge nozzle removably fitted with said barrel, an electric circuit including a motor, a trigger switch fitted in said handle and included in said 15 circuit for the opening and closing thereof, a fan operated by the motor and having communication with the passage in the handle for supplying air under pressure thereto, a liquid container connected with the barrel and in communication 20 therewith, a valve in the handle for opening and closing communication between the passage in the handle and said barrel and carrying the switch, an electric heating unit within the passage 25 in the handle and included in said circuit, a finger engaging piece on the valve and arranged forwardly of the handle, and means for regulating the supply of air under pressure from the fan to the liquid container. 30
